LIGHTING FIXTURE WHICH IS FLEXIBLE AND CAN BE COILED

The present invention concerns a lighting fixture which can be bent as well as coiled, and is specially intended for outside lighting, whereby said fixture can be of considerable length and provided with light points at equal distances or not. Such lighting fixture can be usefully employed for beaconage and lighting of roads, general lighting such as park lighting, advertising signs and the like.

A very considerable advantage of such lighting fixture can for instance be found in the laying of roads and in a general way in such places where visible beacons must be extended over several hundred meters, whereby such beacons must lend themselves to an easy displacement, must be watertight and able to withstand comparatively rough service.

The lighting fixture according to the present invention mainly consists of a transparent tubular element of any convenient length, characterized by the fact that said tubular element is manufactured by making use of an open section which is subsequently folded over so as to form this tubular element; in this section there are at least two longitudinal grooves into which the electrical leads can be housed, and inside aforesaid tubular element, a series of little lamps which make contact with aforesaid electric leads.

According to the present invention, such lighting fixture can either be used for normal lighting, or as a substitute, in other words, as lighting by means of which it is possible to light together and/or alternately two or several rows of colored or noncolored light points, unless in the latter case, one series of light points can be used for normal lighting while the other series is used as a warning sign or the like, such as blinkers, etc.

According to the present invention, aforesaid transparent tubular element is preferably made by starting from an open section which can for instance be obtained by extrusion, whereby said section is provided on one side with at least two longitudinal grooves, while at the other side and at each lateral edge a flange is provided, the arrangement being such that after said element has been formed, aforesaid flanges, outside the element, are fastened to each other.

Also, according to the present invention, the electric leads which are being housed in aforesaid longitudinal grooves, preferably consist of cylindrical wires in order to secure the highest possible deformability of the fixture.

In special modes of embodiment, aforesaid leads can however also assume any other shape, such as a longitudinal strip of material with rectangular cross section, a strip of material folded in zigzag, woven wire, etc.

By making use of such open section, it is particularly easy to apply the lighting bulbs, whereby the sealing of the tubular element around aforesaid bulbs, does not require any special device.

In order to emphasize the particulars of the present invention, without implying any particular limitation, a preferred form of embodiment is described below with reference to the appended drawings of which:

FIG. 1 illustrates in a diagrammatic way a lighting fixture according to the present invention;

FIG. 2 is a perspective view of a part of the transparent tubular element according to the present invention, in which this element is represented in the open condition;

FIG. 3 is a view similar to that of FIG. 2, but after the electric leads have been put into place;

FIGS. 4 and 5 represent in perspective, variants of the electric leads as used in FIG. 3;

FIG. 6 is a cross section of the tubular element according to FIG. 3, after the bulbs have been put into place and after said tube has been brought into the sealed condition;

FIG. 7 is a top view with partial cross section of the tubular element as indicated by arrow F7 in FIG. 6;

FIG. 8 is a cross section by a plane of which the trace follows the straight line VIII-VIII of FIG. 7;

FIG. 9 shows only the lampholder with lamp along a cross section by a plane of which the trace follows straight line IX-IX of FIG. 7;

FIGS. 10 and 11 are respectively cross sections by planes of which the traces follow the straight lines X-X and XI-XI of FIG. 9;

FIG. 12 is a variant of the cross section according to FIG. 11 in order to show that the current can be applied either from left or right, in order to feed two different rows of bulbs for instance.

FIG. 1 illustrates in a diagrammatic way a light fixture 1 conforming to the present invention, which can preferably be closed at both ends and wherein two series of light points 3 and 4 respectively are housed, for which purpose three electric leads 5—6—7 respectively are provided in the fixture and whereby the light points 3 and 4 are so made that the contacts 8 and 9 respectively, are either connected between the leads 5 and 6 or between the leads 6 and 7. In this particular case, lead 6 is for instance connected with the minus pole of a source of current, while leads 5 and 7 are connected to the plus pole of the latter. In this manner by closing switch 11, only the light points 3 light, while by closing switch 12, only the light points 4 will light.

In this way it is therefore obtained that, when the bulbs 3 are of a different color from the bulbs 4, it is possible to light alternately rows of lamps of different colors. It is quite evident that, by inserting a switch in one or other of aforesaid circuits, or in both of them, controlled for instance by a bimetal, it is possible to cause the luminous points 3 and/or 4 to act as blinkers.

It is evident that when the fixture designed in this way is only provided with two electric leads, a flexible lighting fixture is produced which, in this case, will only be fitted with one single series of bulbs.

The source of current 10 may have any convenient voltage and may be for instance a battery of 6, 12, 24v. or of any other voltage and may, on the other hand, be replaced by a connection to the mains with a voltage of 130 v. or 220 v. (or other).

FIG. 2 illustrates the section from which the actual lighting fixture 1 may be manufactured, whereby the latter is preferably made of a transparent or translucid noncolored and comparatively pliable material which, on the one hand, is flexible and which, on the other hand lends itself to being worked by the extrusion process.

Preferably, the material used is polyvinyl chloride. The section used for forming the tubular element 1 consists in this embodiment, of a body 13 in which are provided on one side three longitudinal grooves 14, 15 and 16 respectively, while on the opposite side and facing each one of said grooves, a bulge 17, 18 and 19 is provided in order to avoid weakening the section there where the grooves are provided.

Along each side edge of this section, longitudinal flanges 20, 21 respectively are provided, which are situated on one and the same side of the section and extend at a given angle with respect to aforesaid body 13.

Finally, the ends of aforesaid flanges 20 and 21 are provided with a bead 22 and 23 respectively.

The section which has thus been made is produced for instance by extrusion and will preferably be made of transparent and noncolored polyvinyl chloride.

As illustrated in FIG. 3, the electric leads 24, 25 and 26 respectively are placed in the grooves 14, 15 and 16 and preferably consist of red copper wire-rods. On account of the shape of said leads, it is possible to coil the fixture with a fairly small radius without encountering any particular resistance, whereas on the other hand, the unwinding of such a fixture imposes to the latter only a slight permanent deformation.

FIGS. 4 and 5 illustrate, by way of a variant, two other forms of leads, viz, a simple flat strip 27 and a strip 29 the cross section of which is also rectangular but which is folded in zigzag in order to allow a particular deformation of said leads in special cases.

As illustrated in FIGS. 6 to 12, the actual lamp holder 29 which is being used in this case, is intended for holding L.T. bulbs 30 and consists of a cylindrical tube 31 made of a transparent and comparatively stiff material, such for instance as colorless polyvinyl chloride. Each end of said tube is provided

with a groove 32 and 33 respectively which can cooperate with clamping rings 34 and 35 respectively, of which the inner diameter is designed for exactly fitting over the sockets 36 and 37 respectively of a bulb 30.

Near either of the clamping rings 34 and 35, the body of the tube 31 is provided with passages, or with one passage 38 next to the clamping ring 34 and two passages 39 and 40 respectively next to the clamping ring 35. Each one of these passages is parallel to a dividing line 41, 42 and 43 respectively, which extend at 120° angles of each other, each to said passages being situated at a distance from aforesaid dividing line 41, 42 and 43. Through aforesaid passage 38, there extends an electrode 44 made for instance of a phosphorous bronze strip and comprising a long end 45 which, after the electrode has been fitted into place through passage 38, is exactly pinched between the latter and the inner wall of tube 31 on the one hand, and the corresponding socket 36 of bulb 30 on the hand. Starting from the inner wall of tube 31, the electrode 44 is bent through passage 38 so as to form a part 46 which is parallel to the line 41, after which, outside said tube 31 and in case use would be made of wire-shaped leads, the electrode is bent in such way as to form a semicylindrical end 47 which can subsequently cooperate with the corresponding lead.

According as to whether the bulb 30 is part of the series of bulbs 3 or 4, a second electrode 44 is provided in the same way either through passage 39, or through passage 40, as illustrated in FIGS. 11 and 12, for cooperation with the bulb socket 37.

It is evident that the electrodes can be made in any other way, according to the shape of the lamp holder tubes being used.

The lampholders 29 which are thus formed are provided at equal or unequal distances along the section according to FIG. 3, after which this section is closed around the various lampholders.

This folding or bending is done in such way, that aforesaid flanges 20 and 21, on the outside wall of the element, lean against each other with the result that, on the one hand, aforesaid light sources are firmly held in place, and that additionally the grooves 14, 15 and 16 are more or less distorted (see FIG. 6) so that the leads 24, 25 and 26, and 27 or 28 respectively, are almost enclosed in their respective grooves.

The fastening of aforesaid flanges 20 and 21 against each other may be done in any convenient way, such as by sticking, heat-hardening, riveting, etc.

In order to keep the various lampholders 29 at proper distance from each other, for preventing the leads 24, 25 and 26 from coming out of their grooves and for reinforcing the fixture internally, it is possible to fit between aforesaid lampholders, distance-pieces in the form of hoses made of some flexible material, which may also be polyvinyl chloride for instance.

The lighting fixture which has thus been made is closed at both ends after having been filled with transformer oil if this is required for cooling the bulbs 30.

It is evident that a lighting fixture of this kind could also be fitted with gas-discharge bulbs, such as neon bulbs for in-

stance, in order to reduce overheating as much as possible.

In one particular form of embodiment, little holes could be made in the flanges 20, 21 at given intervals, in order to make it easier to suspend the fixture.

5 In this manner, a lighting fixture is obtained which is practically invulnerable, perfectly sealed and which can be easily rigged up over fairly large distances along any straight or curved track, while it can also be easily coiled after use and that there is also the possibility of making two or several tracks with it by providing two, three or even several electric circuits.

The present invention is not limited to the forms of embodiment mentioned by way of example and illustrated in the appended drawings, but such fixture and electric leads can be designed in any shape, dimensions and combinations, without 10 exceeding the scope of the present invention.

I claim:

1. A lighting fixture, comprising a flexible tubular element having a plurality of grooves extending longitudinally upon the inner surface of said tubular element, a plurality of electrical conductors, each of said conductors being located in a separate groove, at least one tubular lampholder located within said tubular element, at least one electric lamp located in said tubular lamp holder, and electrodes connected with said lamp and with at least two of said electrical conductors to supply electric current to said lamp, wherein said electric lamp comprises two opposed sockets, wherein said tubular lamp holder has a passage close to one of its ends and two separate passages close to the other one of its ends and wherein said electrodes comprise one electrode extending through the first-mentioned passage and connected to one said of said lamp sockets and one of said electrical conductors and another electrode extending through one of said two separate passages and connected to the other one of said lamp sockets and another one of said electrical conductors.

2. A lighting fixture in accordance with claim 1, wherein each of said electrodes has a semicylindrical end portion housing a portion of a separate electrical conductor.

3. A lighting fixture in accordance with claim 1, wherein said passages extend in planes parallel to the longitudinal axis of said tubular lamp holder and equidistant from said axis.

4. A lighting fixture in accordance with claim 1, wherein said tubular lamp holder has sealed ends and is filled with a coolant.

5. A lighting fixture in accordance with claim 1, comprising two clamping rings, each of said clamping rings being carried by a separate end of said tubular lamp holder and engaging a separate socket of said electric lamp.

6. In the manufacture of light fixtures, a flexible channellike element which is substantially U-shaped in cross section and comprises a body and two diverging flanges, the outer surface of said body having a plurality of longitudinal grooves, the opposite surface of said body having a plurality of longitudinal bulges located opposite said grooves, the ends of said flanges having bulges directed substantially toward each other, said flanges being adapted to be bent toward each other over said outer surface to form a closed fixture.
